[57] CLAIM

The ornamental design for a tool for crimping electrical terminal connections or the like, as shown and described.

DESCRIPTION

FIG. 1 is a side elevational view of a tool for crimping electrical terminal connections or the like showing my new design;

FIG. 2 is a rear elevational view thereof;

FIG. 3 is an opposite side elevational view thereof;

FIG. 4 is a front elevational view thereof;

FIG. 5 is a top plan view thereof;

FIG. 6 is a bottom plan view thereof; and

FIG. 7 is a front perspective view thereof.

FIG. 1

FIG. 2

FIG. 3

FIG. 4

FIG. 5

FIG. 6

FIG. 7
